VALVE FOR ROCK DRILLS

Jacob E. Feucht, Garfield Heights, Ohio, assignor
to Le Roi Company, Milwaukee, Wis., a corpora-
tion of Wisconsin

Application May 19, 1948, Serial No. 28,024

6 Claims. (Cl. 121—19)

1

This invention relates broadly to fluid actuated rock drills, but more particularly to a motive fluid distributing valve therefor.

One object of this invention is to provide a rock drill with a fluid distributing valve of simple and efficient construction.

Another object of this invention is to produce a fluid distributing valve for rock drills which affords maximum stroke of the rock drill piston and results in a more efficient tool.

Another object of this invention is to produce a fluid distributing valve for rock drills capable of rapid and positive distribution of the motive fluid alternatively to the ends of the rock drill cylinder for effecting a fast and efficient reciprocation of the rock drill piston.

Other objects and advantages more or less ancillary to the foregoing reside in the specific construction and arrangement of the elements peculiar to this structure, as will become apparent from a more complete examination of this specification.

In the drawing:

Figure 1 is a longitudinal sectional view of a portion of a rock drill embodying the invention.

Figure 1A is an enlarged view of a portion of the valve mechanism as shown in Figure 1.

Figure 2 is a view corresponding to Figure 1 but showing the valve and piston in another position.

Figure 2A is an enlarged view of a portion of the valve mechanism as shown in Figure 2.

Figure 3 is a cross sectional view taken in a plane indicated by line 3—3 in Figure 2.

Figure 4 is a cross sectional view taken in a plane indicated by line 4—4 in Figure 1.

Referring to the drawing in which like symbols designate corresponding parts throughout the several views, 10 represents the main cylinder of a rock drill, which cylinder is normally closed by a back head 12 and tappet case 14, and has its interior accurately machined to form a piston chamber 16 within which is reciprocably mounted a piston 18. As shown in the drawing, the right hand portion of the piston chamber 16, hereinafter referred to as the front or front portion, has extending thereto the shank 20 of a tappet (not shown) on which the piston 18 is adapted to deliver its impacts, which are transmitted thereto to the cutting tool in the usual manner. Fitted within the other end portion of the cylinder 10, hereinafter designated as the rear or rear portion of the piston chamber, there is a valve mechanism which includes a stationary valve casing 21 having a central bore 22 extending through the front end thereof and two counterbores 23

2

and 24 extending rearwardly from the bore 22. The counterbore 23 is made with a flat bottom 25, hereinafter referred to as a front valve seat, which seat is diametrically extended beyond the normal wall of the counterbore 23 by a circular groove 26 maintained in constant communication with the rear portion of the piston chamber 16 through a plurality of rear inlet ports 28, one of which is shown in Figures 1 and 2. The bottom of the counterbore 24 is constantly vented to the exterior of the cylinder through a vent port 27.

Mounted for free reciprocation within the valve casing 21 but in fluid tight engagement with the walls of the counterbores 23 and 24, there is a sleeve valve 29 having its front end 30 perfectly machined for fluid tight engagement with the valve seat 25. For a short distance from the front end 30, the diameter of the valve 29 is reduced to provide a front lifting or shifting area 31.

In the casing 21, there is a stationary valve bushing 32 which has its rear end portion closely fitted within the counterbore 24 and its front end portion reduced to fit closely within the central bore 22 of the casing 21, thereby maintaining the valve bushing in perfect alignment with the casing. Intermediate its ends, the valve bushing is provided with two cylindrical reduced portions 33 and 34 fitting within the interior of the valve 29 in sliding engagement therewith, and forming two annular areas 35 and 36, the area 35 being accurately machined to form a flat rear valve seat engageable by the adjacent rear end 37 of the valve. The length of the bushing reduced portion 33 is made somewhat shorter than the corresponding depth of the valve, so that the area 36 is not engageable by the corresponding step or area 38 of the valve, which area 38 forms a rear shifting area in communication with the piston chamber 16 through a kick port 39.

The bushing 32 is internally machined to provide a chamber 40 which opens into a chamber 41 provided within the back head 12. These two chambers form a reservoir for motive fluid which may be admitted therein through a supply port 42 controlled by a throttle valve 43. This throttle valve may be of any suitable type and is provided with a central bore or passage 44 to which motive fluid is admitted from a source of supply.

Adjacent the front end 30 of the valve 29, the bushing 32 is chamfered to form with the valve seat 25 and the interior of the valve when positioned as shown in Figures 1 and 1A, a second motive fluid supply chamber 45, which chamber is in constant communication with the chamber 40 through inlet ports 46.

Also supplying motive fluid to the rear valve

seat 35, there is a plurality of ports 47 extending radially from the chamber 40 through the bushing 32. From the valve seat 35 motive fluid may be admitted into the front portion of the piston chamber 16 through front inlet ports 48 which open into an annular groove 49 cut into the inner wall of the cylinder adjacent the front end thereof. To enlarge the volumetric capacity of the front piston chamber, the groove 49 is also in communication with a plurality of blind ports 50, one of which is shown in Figures 1 and 2, while the back piston chamber is similarly enlarged by blind ports 51 opening thereinto adjacent the valve casing 21. Intermediate its ends, but located closer to the front than the rear end thereof, the piston chamber 16 is provided with an exhaust groove 52 which is connected to the exterior of the cylinder through one or more exhaust ports 53.

Referring now to the operation of this valve mechanism, it will be understood that with the throttle valve 43 open, motive fluid such as compressed air will flow into the first inlet chamber 40-41 through the port 42. With the piston 18 and valve 29 positioned as shown in Figures 1 and 1A, motive fluid from the interior of the bushing 32 will flow to the rear valve seat 35 and act on the rear end or rear holding area 37 of the valve for maintaining it in its forward position. With the valve in its forward position, motive fluid from the valve seat 35 is free to flow into the front portion of the piston chamber 16 through the front inlet ports 48 and groove 49.

In the position of the piston 18 shown in Figure 1, that is engaged with the tappet shank 20 to deliver its impact thereon, the piston has uncovered the exhaust groove 52, enabling communication of the rear portion of the piston chamber 16 with the exterior of the cylinder and a free return stroke of the piston, which stroke is effected by the action of the motive fluid admitted into the front portion of the piston chamber.

During its return or back stroke, the piston will first cover the exhaust groove 52 and the inlet end of the kick port 39, and thereafter will compress air remaining within the rear end portion of the piston chamber 16. The air thus compressed will act on the valve front shifting area 31, it being admitted thereto through the rear inlet ports 28, tending to shift the valve rearwardly. However, motive fluid is still active on the valve rear holding area 37, and since this area is greater than the area 31, the valve will remain in the position shown in Figures 1 and 1A until the front end of the piston uncovers the exhaust groove 52 to enable exhaust of the motive fluid from the front end of the piston chamber 16. This sudden exhaust will cause a drop of pressure of the motive fluid acting on the valve rear holding area 37, allowing the valve to shift to the position shown in Figures 2 and 2A.

In this new or rear position of the valve, motive fluid from the second supply chamber 45 will act on the valve front holding area 30 and front shifting area 31 to maintain the valve in its rear position. Simultaneously, motive fluid from the same chamber 45 will flow through the rear inlet ports 28 into the rear end of the piston chamber 16 to act on the piston for driving it forward against the tappet shank 20.

During its forward stroke, the rear end of the piston will uncover the inlet end of the kick port 39, thereby allowing motive fluid from the piston chamber 16 to flow to the valve rear shifting area 38. Since this last area is larger than the front

shifting area 31 and front holding area 30, the valve will immediately shift to its forward position. During the end of its forward stroke, the piston will also uncover the exhaust groove 52 to allow exhaust of the motive fluid previously admitted into the rear end of the piston chamber 16, as well as exhaust of the motive fluid from the valve rear shifting area 38 through the kick port 39, which port is now in communication with the exhaust groove 52 through the piston chamber 16. The forward stroke of the piston will end as the piston strikes the tappet shank 20.

As previously explained, the valve is held in its forward position by the action of the motive fluid on the valve rear holding area 37, while motive fluid is again admitted into the front end of the piston chamber 16 through the front inlet ports 48 for driving the piston rearwardly, thus completing the cycle.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope and spirit of the invention as herein claimed.

I claim:

1. In a fluid actuated rock drill, a cylinder having a piston chamber, a piston reciprocable in said chamber, an exhaust port for the piston chamber controlled by said piston, a valve casing having opposed front and rear flat annular valve seats, a sleeve valve reciprocable within said casing, means internally of said valve for constantly supplying motive fluid to said seats, front and rear inlet ports leading from the correspondingly named valve seats into the front and rear portions of said piston chamber for alternatively admitting motive fluid therein to effect reciprocation of said piston, the opposed ends of said valve being movable into and out of fluid tight engagement with said valve seats by virtue of the reciprocity of the valve for controlling admission of the motive fluid into the front and rear portions of said piston chamber, the ends of said valve when moved out of said fluid tight engagement forming holding areas subjected to the action of the motive fluid constantly supplied to said valve seats for holding the valve out of said fluid tight engagement, and means effecting reciprocation of said valve including an internal shifting area on said valve intermittently subjected to motive fluid from the rear portion of said piston chamber when said piston reaches a predetermined position therein during its forward stroke for shifting said valve in a position preventing supply of motive fluid to said rear inlet ports, and an external shifting area on said valve subjected to fluid compressed within the rear portion of said piston chamber during the rear stroke of said piston tending to shift said valve in a position preventing supply of motive fluid to said front inlet ports, this last movement of the valve occurring after the pressure of the motive fluid acting on the valve holding area for maintaining the valve in the position to be shifted from has been reduced by virtue of the exhaust of the motive fluid from the front end portion of said piston chamber through said exhaust port.

2. In a fluid actuated rock drill, a cylinder having a piston chamber, a piston reciprocable in

said chamber, an exhaust port for the piston chamber controlled by said piston, a valve casing having opposed front and rear flat annular valve seats, a sleeve valve reciprocable within said casing, means internally of said valve for constantly supplying motive fluid to said seats, front and rear inlet ports leading from the correspondingly named valve seats into the front and rear portions of said piston chamber for alternatively admitting motive fluid therein to effect reciprocation of said piston, the opposed ends of said valve being movable into and out of fluid tight engagement with said valve seats by virtue of the reciprocation of the valve for controlling admission of the motive fluid into the front and rear portions of said piston chamber, the ends of said valve when moved out of said fluid tight engagement forming holding areas subjected to the action of the motive fluid constantly supplied to said valve seats for holding the valve out of said fluid tight engagement, and means effecting reciprocation of said valve including opposed internal and external valve shifting areas, the internal area being intermittently subjected to valve shifting motive fluid from the rear portion of said piston chamber during the forward stroke of the piston and the external area being intermittently subjected to valve shifting fluid compressed in said rear portion of the piston chamber by the piston during its rearward stroke.

3. In a fluid actuated rock drill, a cylinder having a piston chamber, a piston reciprocable in said chamber, an exhaust port for the piston chamber controlled by said piston, a valve casing having opposed front and rear flat annular valve seats, a sleeve valve reciprocable within said casing, means internally of said valve for constantly supplying motive fluid to said seats, front and rear inlet ports leading from the correspondingly named valve seats into the front and rear portions of said piston chamber for alternatively admitting motive fluid therein to effect reciprocation of said piston, the opposed ends of said valve being movable into and out of fluid tight engagement with said valve seats by virtue of the reciprocation of the valve for controlling admission of the motive fluid into the front and rear portions of said piston chamber, the ends of said valve when moved out of said fluid tight engagement forming holding areas subjected to the action of the motive fluid constantly supplied to said valve seats for holding the valve out of said fluid tight engagement, and means effecting reciprocation of said valve including opposed internal and external valve shifting areas, said external area being intermittently subjected to valve shifting fluid compressed in the rear portion of the piston chamber by the piston during its rearward stroke, and a kick port leading from said internal area to said piston chamber, said kick port being controlled by said piston for admitting valve shifting motive fluid to said internal area.

4. In a fluid actuated rock drill, a cylinder having a piston chamber, a piston reciprocable in said chamber, an exhaust port for the piston chamber controlled by said piston, a valve casing having opposed front and rear flat annular valve seats, a sleeve valve reciprocable within said casing, means internally of said valve for constantly supplying motive fluid to said seats, front and rear inlet ports leading from the correspondingly named valve seats into the front and rear portions of said piston chamber for alternatively admitting motive fluid therein to effect reciprocation of said piston, the opposed ends of said valve being mov-

able into and out of fluid tight engagement with said valve seats by virtue of the reciprocation of the valve for controlling admission of the motive fluid into the front and rear portions of said piston chamber, the ends of said valve when moved out of said fluid tight engagement forming holding areas subjected to the action of the motive fluid constantly supplied to said valve seats for holding the valve out of said fluid tight engagement, and means effecting reciprocation of said valve including opposed internal and external valve shifting areas, a kick port leading from said internal area to said piston chamber, said kick port being controlled by the piston during its forward stroke for intermittently admitting valve shifting motive fluid to said internal area, said external area being intermittently subjected to valve shifting fluid compressed in the rear portion of the piston chamber by the piston during its rearward stroke, said external area after the shift of the valve by virtue of the compressed fluid acting thereon being also subjected to motive fluid constantly admitted to one of said valve seats for holding the valve away from said one valve seat.

5. In a fluid actuated rock drill, a cylinder having a piston chamber, a piston reciprocable in said chamber, an exhaust port for the piston chamber controlled by the piston, a valve casing having a front flat annular valve seat, a valve bushing in said casing having a rear flat annular valve seat, a sleeve valve reciprocable in said casing and on said bushing capable of end engagement with said valve seats, a first motive fluid supplying chamber internally of said bushing, front inlet ports leading from said last chamber to the rear valve seat and therefrom to the front end portion of said piston chamber for supplying motive fluid thereinto to effect the rearward stroke of said piston, the supply of motive fluid through said front inlet ports being shut off by engagement of the valve with said rear valve seat, a second motive fluid supplying chamber externally of said bushing, ports affording constant communication between said first and second chambers, means for supplying motive fluid from said second chamber into the rear portion of said piston chamber for effecting the forward stroke of said piston including rear inlet ports, the supply of motive fluid through said rear inlet ports being shut off by engagement of the valve with said front valve seat, and means for effecting the reciprocation of said valve including opposed valve shifting areas alternatively subjected to valve shifting fluid from said piston chamber.

6. In a fluid actuated rock drill, a cylinder having a piston chamber, a piston reciprocable in said chamber, an exhaust port for the piston chamber controlled by the piston, a valve casing having a front flat annular valve seat, a valve bushing in said casing having a rear flat annular valve seat, a sleeve valve reciprocable in said casing and on said bushing capable of end engagement with said valve seats, a first motive fluid supplying chamber internally of said bushing, front inlet ports leading from said last chamber to the rear valve seat and therefrom to the front end portion of said piston chamber for supplying motive fluid thereinto to effect the rearward stroke of said piston, the supply of motive fluid through said front inlet ports being shut off by engagement of the valve with said rear valve seat, a second motive fluid supplying chamber externally of said bushing, ports affording constant communication between said

first and second chambers, means for supplying motive fluid from said second chamber into the rear portion of said piston chamber for effecting the forward stroke of said piston, including rear inlet ports, the supply of motive fluid through said rear inlet ports being shut off by engagement of the valve with said front valve seat, and means for effecting the reciprocation of said valve including opposed valve shifting areas alternatively subjected to valve shifting fluid from said piston chamber, and holding areas for said valve formed by the ends thereof and subjected to motive fluid from said supply chambers for temporarily holding the valve at the end of its strokes.
